3 Claims

ABSTRACT OF THE DISCLOSURE

A method of fabricating a spark gap in which a movable electrode extends into the gap through a hollow tube and the spacing of the gap is set prior to exhausting and sealing off the gap.

The present invention relates to electron discharge devices and more particularly to spark gaps and to the method of making the same.

The breakdown voltage of spark gaps depends substantially upon the pressure-gap spacing relationship. Present sealing techniques are such that extremely close tolerances in gap spacing are difficult to maintain. This makes it necessary, in producing gaps which have close tolerances in spacing, to fill them individually to a predetermined breakdown voltage. Thus it is necessary to apply the predetermined voltage across the gap and allow the gas to enter until the discharge occurs.

The present invention provides a spark gap assembly which can be adjusted accurately to any spacing within a predetermined range after sealing in and prior to exhausting and filling. In accordance with the invention, a tight tolerance in the order of $\pm 001"$ can be maintained. Pressure can then be determined for a given gas and spacing of the electrodes, thus enabling a plurality of devices to be filled at one time on a system. All of the devices would be within a predetermined range of breakdown voltages.

It is an object of the invention to provide an improved electron discharge device.

Another object of the invention is to provide an improved spark gap.

Another object of the invention is to provide a novel method for fabricating a spark gap.

Another object of the invention is to provide an improved method of fabricating a spark gap in which the electrodes can be accurately spaced.

Another object of the invention is to provide a high volume, low cost method of producing spark gaps.

Another object of the invention is to provide a method of adjusting gap spacing in a spark gap having an opaque envelope.

The above and other objects and features of the invention will appear more fully hereinafter from a consideration of the following description taken in connection with the accompanying drawings wherein one example is illustrated by way of example.

In the drawing:

FIG. 1 is a sectional view of a device illustrating the invention.

FIG. 2 is a sectional view of fixed electrodes for use in devices made in accordance with the invention.

FIG. 3 is a sectional view of adjustable electrodes for use in devices made in accordance with the invention.

FIG. 4 is a diagrammatical view of a typical adjusting device.

Referring now to the drawing, a spark gap is indicated generally by the numeral 5 and includes an envelope 6 of a suitable material such, for example, as glass. It is understood, however, that other material could be used

2

for the envelope. A fixed electrode 7 is sealed in one end of the envelope 6 by a glass to metal seal 8. The electrode 7 includes a stem section 9 of a hollow metallic rod of a suitable material, for example, a nickel-iron-cobalt alloy commonly known as "Kovar." Attached to the stem section 9 by welding or any other suitable manner is an electrode section 10 of a suitable material, for example, a refractory metal. It is understood that the electrode section could be of other configuration than that shown, as an example, it could be similar to that shown in FIG. 2 as 10A. Other configurations could also be used. An opening 11 is provided in the stem 9 to permit exhausting and filling the envelope with a suitable gas. An exhaust tubulation 12 is attached to the stem 9 in a conventional manner.

An adjustable electrode assembly 13 is sealed in the other end of the envelope 6 by a glass to metal seal 14. The assembly 13 includes a hollow tube 15 of a suitable material, for example, "Kovar." Inserted in the tube 15 is 20 a rod-like stem member 16, which may be of the same material as the tube 15. Normally the stem member 16 will have an O.D. slightly less than the I.D. of the tube 15, for example .005". Attached to the stem member 16 by welding or in any other manner is an electrode member 17 of a refractory metal. The configuration of the electrode 17 may be those illustrated in FIG. 3 or any other suitable configuration.

The spacing between the fixed electrode 10 and the hollow tube 15, the distance A of FIG. 1, for spark gaps 30 to cover a predetermined range is proportioned so that when the adjustable electrode 17 is pulled back all the way, the gap spacing, the distance B of FIG. 1, will be sufficient to provide for the maximum required breakdown for the predetermined range. The length of the stem 35 16, the distance C of FIG. 1, is proportioned to permit sufficient movement of the electrode 17 to obtain the minimum gap spacing required in the predetermined range.

The devices as set forth above may be made in quantities large enough to warrant an automatic sealing set 40 up and to be stocked. When gaps having certain predetermined characteristics are desired, the spacings are adjusted on an appropriately accurate measuring device to the correct gap spacing to provide the predetermined characteristics. The tube 15 is then crimped to fix the stem 16 and thereby the gap spacing "B." The excess of the tube 15 and stem 16 is then cut off and a hermetic weld made between the tube 15 and stem 16. The device is then exhausted and filled to a predetermined pressure of a suitable gas or mixtures of gas and then tipped and sealed off.

Reference is now made to FIG. 4 wherein one embodiment of a gap positioning device is illustrated. An adjusting fixture is indicated generally by the numeral 20 and includes a base 21. Mounted on the base 21 is a pair of clamps 22 adapted to receive the device 5 and to hold the same in a fixed position. Also mounted on the base 21 is a micrometer adjusting screw 23 adapted for engagement with the rod 16 of the adjustable electrode assembly 60 13, thus permitting micrometer adjustment of the electrode spacing "B."

Although only one embodiment of the invention has been illustrated and described, various changes in the form and relative arrangement of the parts, which will now appear to those skilled in the art, may be made without departing from the scope of the invention.

What is claimed is:

1. A method of fabricating a spark gap comprising the steps of sealing in a fixed electrode in an envelope, mounting a movable electrode on a rod-like member, placing said rod-like member in a hollow tube, sealing said hollow tube in said envelope with said movable elec-

trode located within said envelope, adjusting said movable electrode to a predetermined position by moving said rod-like member in said tube, fixing said movable electrode in said predetermined position by permanently connecting said rod-like member and said tube, and forming a seal between said rod-like member and tube.

2. The method of claim 1, in which said movable electrode is fixed and sealed to said tube by crimping said hollow tube on said rod-like member and weld-sealing said tube and member to one another.

3. A method of fabricating a spark gap having a pair of electrodes enclosed in an envelope comprising the steps of mounting one of said electrodes on one end of a hollow stem, sealing said hollow stem in one end of said envelope, connecting the other end of said stem to an exhaust tubulation, mounting the other of said electrodes on a rod-like member, inserting said rod-like member in a hollow tube, sealing said hollow tube in the other end of said envelope, adjusting the spacing between said electrodes to a predetermined value by moving said rod-like member in said tube permanently, securing said other electrode in a fixed position in said hollow tube by crimping and welding said hollow tube and said rod-like member to form an hermetic seal external of said envelope between said rod-like member and said hollow tube, exhausting and filling said envelope to a predetermined pressure of a gas, and tipping off and sealing said hollow stem.
